UNITED STATES PATENT OFFICE.

FRANCIS H. RICHARDS, OF HARTFORD, CONNECTICUT, ASSIGNOR TO THE KEMPSHALL MANUFACTURING COMPANY, OF ARLINGTON, NEW JERSEY, A CORPORATION OF NEW JERSEY.

PLAYING-BALL.

SPECIFICATION forming part of Letters Patent No. 720,737, dated February 17, 1903.

Application filed October 6, 1902. Serial No. 126,021. (No model.)

To all whom it may concern:

Be it known that I, FRANCIS H. RICHARDS, a citizen of the United States, residing at Hartford, in the county of Hartford and State of Connecticut, have invented certain new and useful Improvements in Playing-Balls, of which the following is a specification.

This invention, relating to playing-balls, and especially those adapted for the purpose of golf, has for its object to provide at low cost and by the use of cheap material a ball possessing the triple qualities of "putting," "approach," and "long drive."

The accompanying illustration embodies one form of the invention, the ball being represented partly broken away to disclose the construction.

I use a hard center piece A—such as celluloid, gutta-percha, or metal—to which is applied a soft layer B, preferably of soft rubber. Inclosing the structure thus formed is preferably a thick layer C, of leather, hide, or other like fibrous material. This layer in the present instance comprises scraps of leather 4, which are compressed together under high pressure and which are formed into segments 5 and 6. The segments 5 and 6 are previously formed by compressing loose scraps 4 of leather under high pressure with some heat, if preferred, so as to compact them and produce a high degree of resilience in the structure. Each scrap of leather possesses a certain amount of mobility, and by combining a number of them into one body the mobility contained in each scrap is transmitted to the structure as a whole, whereby a considerable amount of resilience is stored up in the ball. If desired, within the scope of this invention I may apply to this scrap a solution of adhesive, whereby under heat and pressure said scraps will become united one to another, so that greater degree of solidity is obtained, and whereby the leather scrap is retained in a compressed condition, thus improving its springy quality. On the outside of this layer C, I wind in miscellaneous directions a quantity of cordage or yarn D and finally inclose the structure with a hard shell E, such as gutta-percha, celluloid, or the like. It will be seen that a ball built in this manner pos-

sesses a relatively dead quality for a putting blow, a local resiliency at the point where the blow is struck for the approach, and a general resilience throughout the ball for bringing out the maximum resilience when the ball is struck a quick sharp blow for a long drive.

It will also be seen that this ball has the advantage of durability and efficiency and can be made of materials easily attainable at a relatively low cost. It will also be noted that the resilient leather layer is cushioned between the center piece and the outer shell by the soft plastic layer and a layer of yarn.

Variations of construction as shell and materials and disposition thereof may be resorted to within the scope of this invention.

Having described my invention, I claim—

1. A playing-ball comprising a hard center piece, a shell of soft rubber thereon, hemispherical segments of compressed scraps of fibrous material inclosing said center piece, and layers of yarn wound thereon in miscellaneous directions, and a shell of gutta-percha. 70

2. A playing-ball comprising a hard but springy center piece, a shell of plastic material thereon, hemispherical segments of leather scraps consolidated under heat and pressure inclosing said center piece, windings of yarn thereon, and a shell of gutta-percha. 75

3. A playing-ball comprising a hard but springy center piece, a shell of plastic material thereon, hemispherical segments of scraps of leather consolidated under heat and pressure and inclosing said center piece, windings of 85 yarn thereon, and a shell of plastic material.

4. A playing-ball, a portion whereof comprises a layer built up of hemispherical segments of scrap-leather consolidated together under heat and pressure. 90

5. A playing-ball comprising a center piece, a spherical layer thereon consisting of leather scraps in a compressed condition, and a cover of plastic material.

6. A playing-ball comprising a center piece, 95 a spherical layer thereon consisting of leather scraps in a compressed condition and mixed with an adhesive, and a cover.

7. A playing-ball comprising a center piece, hemispherical segments thereon consisting of 100

- leather scraps in a compressed condition and mixed with an adhesive, and a cover of plastic material.
8. A playing-ball comprising a sphere consisting of leather scraps in a compressed condition and mixed with an adhesive, and a cover.
9. A playing-ball comprising a sphere consisting of leather scraps in a compressed condition, tense windings of binding material thereon, and a cover.
10. A playing-ball comprising a sphere of soft rubber, a sphere thereon consisting of compressed leather scraps, and a cover.
11. A playing-ball comprising a sphere of soft rubber, a sphere thereon consisting of compressed leather scraps, tense windings of binding material upon said sphere, and a cover.
12. A playing-ball comprising a soft-rubber sphere, a sphere thereon consisting of leather scraps in a compressed condition and mixed with an adhesive, and a cover.
13. A playing-ball comprising a soft-rubber sphere, a sphere thereon consisting of leather scraps in a compressed condition and mixed with an adhesive, and a gutta-percha sphere.
14. A playing-ball comprising a soft-rubber sphere, a sphere thereon consisting of leather scraps in a compressed condition and mixed with an adhesive, tense windings of binding material upon said leather scrap, and a gutta-percha cover.
15. A playing-ball comprising a hard center piece, a layer of soft rubber thereon, a layer upon said soft rubber consisting of leather scraps under compression and mixed with an adhesive, tense windings of binding material upon said scraps, and a cover of gutta-percha.

Signed at Nos. 9 to 15 Murray street, in the city and State of New York.
